DESIGN FOR A WATCH

Leon M. Newhouse, Brooklyn, N. Y., assignor to
Longines-Wittnauer Watch Co., Inc., New York,
N. Y.

Application October 29, 1947, Serial No. 142,195

Term of patent 14 years

(Cl. D42—8)

To all whom it may concern:

Be it known that I, Leon M. Newhouse, a citizen of the United States of America, residing at Brooklyn, New York, county of Kings, and State of New York, have invented a new, original, and ornamental Design for a Watch, of which the following is a specification, reference being had to the accompanying drawings, forming a part thereof.

Fig. 1 is a plan view of a watch, showing the essential features of my design in full lines;

Fig. 2 is an enlarged perspective view of the full line disclosure in Fig. 1; and

Fig. 3 is a fragmentary plan view of the disclosure in Fig. 2.

I claim:

The ornamental design for a watch, substantially as shown and described.

LEON M. NEWHOUSE.
